UNITED STATES PATENT OFFICE.

WILLIAM DUCHEMIN, OF BOSTON, MASSACHUSETTS.

SEAM-STAY GUIDE FOR SEWING-MACHINES.

SPECIFICATION forming part of Letters Patent No. 245,287, dated August 9, 1881.

Application filed April 1, 1880. (No model.)

To all whom it may concern:

Be it known that I, WILLIAM DUCHEMIN, a subject of her Britannic Majesty, residing at Boston, in the county of Suffolk and State of Massachusetts, have invented a new and useful Seam-Stay Guide for Sewing-Machines, of which the following is a specification.

The object of my invention is to construct the throat-plates of sewing-machines in such a manner that they will serve as stay-guides, and this object is accomplished by the construction illustrated in the accompanying drawings, in which—

Figure 1 is a plan view of a throat-plate constructed according to my invention. Fig. 2 is a similar view, showing the feed-dog in position. Fig. 3 is an under side view. Fig. 4 is a partial longitudinal section on the line 3 3, Fig. 1. Figs. 5, 6, and 7 are cross-sections of my throat-plate; and Fig. 8 represents a stay-piece.

A represents a throat-plate having the usual feed-opening, b, and needle hole or throat c. A recess or passage, d, is formed in the under side of said throat-plate, said passage extending horizontally from the front end thereof to a point opposite the feed-opening b, when it is inclined gently upward through the top surface of the throat-plate, at a, thus forming, in connection with the bed g of the machine, an inclosed and continuous passage through which a staying-piece may be fed to the needle for the purpose of uniting the said staying-piece to the fabric being sewed.

The recess or passage d may be made of any desired width, according to the width of the staying-piece which is to be used. This passage d opens at one side into the feed-opening, and from the point h toward the front end of the throat-plate one side of said passage is inclined at a small angle from the other side, so that said passage converges or grows gradually narrower from the end of the throat-plate to point h, as shown in the drawings.

In the use of my device the stay-piece is introduced through the passage d, and is drawn

up through the opening a above the feed-dog c and beneath the fabric being sewed, and is fed forward with the fabric and united therewith by the usual stitch-forming devices. 50

If a wide margin of the stay-piece outside of the line of stitching is required, the stay-piece must be the width of the front end of the passage d, and to introduce said stay-piece it will be convenient to cut it in the form shown 55 at Fig. 8. Thus when the stay-piece is drawn forward one side thereof will press against the feed-dog c, and when said dog falls below the surface of the throat-plate, the passage d being open on the side toward the feed-dog, the extra width of the stay-piece presses outward 60 and is flattened out on the feed-dog by the presser-foot of the machine.

If only a small margin of the stay-piece outside of the line of stitching is desired, said stay-piece will be only the width of the passage d opposite the feed-opening b. 65

I am aware that it is not new to provide a throat-plate with a passage-way for guiding a strip of braid or other fabric to the stitch-forming mechanism of a sewing-machine, and I do not therefore claim such construction, broadly; 70 but

What I do claim, and wish to secure by Letters Patent, is—

The sewing-machine throat-plate A, having the converging passage d extending horizontally from one end of said throat-plate to a point opposite the feed-opening b, and then inclined upward through the top surface of said 80 throat-plate, said passage d being open at that part thereof opposite said feed-opening, substantially as and for the purpose specified.

In testimony whereof I have signed my name to this specification, in the presence of two subscribing witnesses, this 20th day of March, A. D. 85 1880.

WILLIAM DUCHEMIN.
